JOHN L. BOYLE, OF BOSTON, MASSACHUSETTS.

CONTROLLING DEVICE FOR SELF-FOCUSING ELECTRIC-ARC LAMPS.

1,262,916.

Specification of Letters Patent. Patented Apr. 16, 1918.

Substitute for application Serial No. 741,672, filed January 13, 1913. This application filed March 31, 1916. Serial No. 87,904.

To all whom it may concern:

Be it known that I, JOHN L. BOYLE, a citizen of the United States, residing at Boston, in the county of Suffolk and State of 5 Massachusetts, have invented an Improvement in Controlling Devices for Self-Focusing Electric-Arc Lamps, of which the following is a specification.

This invention relates to controlling devices for electric arc lamps and is a substitute for application, Serial #741672, filed January 13, 1913.

The object of the invention is to provide controlling-means for an electric arc lamp 15 whereby the arc shall be automatically maintained at a predetermined point, such for example as the optical center of a lens with which the lamp is employed. Although the invention is shown in connection with what 20 is commonly termed a focusing arc lamp it will be understood that it is also adapted for use with a non-focusing arc lamp.

One form of the invention contemplates the provision of electro-responsive means 25 controlled by the current passing from one to the other electrode for lowering or raising the arc according as the center of the same moves up or down with respect to a predetermined point, caused by the consumption of the electrodes. In carrying out this form of the invention a contact-member 30 is provided, which is adapted to make contact with one or the other or both of the electrodes adjacent the arc, and this contact-member is common to two circuits, each circuit containing an electro-responsive device arranged to control actuating-means by 35 which the lamp is raised and lowered, and the arc maintained at a predetermined point, one of said circuits being connected to the 40 upper electrode and the other circuit being connected to the lower electrode.

The heat of the ordinary arc is very intense, so that it is preferable to move the 45 contact-member intermittently into and out of contact therewith or with the electrodes at short intervals, but as said contact-member may remain continuously in contact with the arc, at least for a short period of time, I 50 have, therefore provided means for practising my invention, suitable to both of these conditions.

A further feature of the invention contemplates the provision of a positive stop which is arranged to be inserted periodically between the electrodes, and then the electrodes are brought into engagement therewith to relocate the arc. 55

I will describe my invention in the following specification, and will point out the 60 novel features thereof in the appended claims.

In the accompanying drawings,

Figure 1 is a diagrammatic view illustrating one embodiment of the invention, 65 suitable for use with an ordinary arc.

Fig. 2 is a plan view of the mechanism for raising and lowering the arc.

Fig. 3 is a side elevation of the mechanism 70 shown in Fig. 2.

Fig. 4 is a plan view of the mechanism for controlling the circuits of the raising and lowering mechanism.

Fig. 5 is a side elevation of the same.

Fig. 6 is a side elevation of the mechanism 75 for actuating the contact which engages the electrodes.

Figs. 7, 8 and 9 are details of the mechanism for periodically closing the circuit which actuates the contact. 80

Fig. 10 is a diagrammatic view of a modified form of the invention.

Fig. 11 is a diagrammatic view of another modified form of the invention.

Fig. 12 is a diagrammatic view of still 85 another modified form of the invention.

As illustrated in Figs. 1 to 9, inclusive, 10 represents a housing for an electric arc lamp, which may be of the well-known focusing type, having an upper electrode 12 90 and a lower electrode 14. The lamp is designed to be arranged upon any suitable adjustable support or table 16, so that the position of the arc 18, formed between the electrodes 12 and 14, may be vertically adjusted as desired with respect to a predetermined point, such as the optical center of a lens, or the like. The electrodes are preferably extra long and means may be provided for keeping them in perfect alinement. 95

Arranged so as to engage either or both of the electrodes 12, 14, is a contact-member 20, which may be of carbon or other suitable material. This contact-member is arranged

to be moved periodically into and out of engaging position by mechanism which will be hereinafter described. When the arc is in its correct position and the contact-member 20 is moved into engaging position it may engage the arc only, but when the arc has shifted to a position above or below the predetermined point, due to the consumption of the electrodes, said contact-member will engage one or the other of said electrodes according to which direction the arc has shifted.

The upper electrode 12 is connected by a wire 22 to coil 23 of an electro-responsive device, such as a relay-switch, and said coil is connected by wires 24, 25, to the contact-member 20. The lower electrode 14 is connected by a wire 28 to coil 30, of an electro-responsive device, such as a relay-switch, and said coil is connected by a wire 31 to the wire 25, which leads to the contact-member 20. Thus there are two circuits having a common conductor 25 connected to the contact-member 20, each circuit containing an electro-responsive device. Said devices or relay-switches are adapted to control mechanism for moving the lamp bodily up or down as required.

The mechanism here shown for raising and lowering the lamp comprises a pair of electro-magnet coils 32, 34, arranged in a suitable housing 35 which contains the support or table 16. The coil 32 is connected by a wire 36 to a stationary contact-member 37, and is connected by wires 38 and 39 to a supply-wire 40. The coil 34 is connected by a wire 42 to the wire 39, and is connected by a wire 44 to a stationary contact-member 45. A stationary contact-member 46, adjacent the contact-member 45 is connected to the supply-wire 48, and a stationary contact-member 49, adjacent the contact-member 39 is connected by a wire 50 to the said supply-wire 48. The contact-members 45 and 46 are adapted to be bridged by a switch-arm 52 carried by an armature 53 for the coil 23, and the contact-members 37 and 49 are adapted to be bridged by a switch-arm 54 carried by an armature 55 for the coil 30.

The electro-magnets 32, 34, are preferably solenoids having slidable iron cores or plungers 60, 61, respectively, arranged to pass through guides 62. The inner end of each core is connected to the corresponding end of a brass or other non-magnetic rod 64, slideable through a guide 66, and provided at its outer end with a cross-bar 68. The ends of each cross-bar are connected to retractile springs 69, 70, which are attached to adjusting-screws 72, 73, by means of which the tension of said springs is adjusted.

A pawl 74 is pivotally connected to the

outer end of the core 60 and is held in yielding engagement with a ratchet-wheel 76, by a spring 77; and a pawl 78 is pivotally connected to the outer end of the core 61 and held in engagement with a ratchet-wheel 80 by a spring 81. The pawls 74 and 78 are normally out of engagement with the ratchet-wheels 76 and 80, respectively, but are brought into engagement therewith by the movement of the cores 60 and 61, respectively, when their respective coils 32 and 34 are energized. The ratchet-wheels 76 and 80 are fast on a vertical shaft 82 journaled in a supporting-base 84, and provided at its upper end with a screw-threaded portion 86 which engages a nut 87 supported by brackets 88 depending from the under side of the table 16. A pair of sockets 90 are secured to the under side of the table 16 and receive guide-rods 91 which project upward from the base 84. When the coil 32 is energized its core 60 is drawn in and the ratchet-wheel 76 is rotated clockwise thus turning the screw 86 to raise the table 16, the cross-bar 68 is moved outward and the springs 69 and 70 are put under tension. When the coil 32 is deenergized the core 60 and connected parts are returned to normal position, as shown in Fig. 2. When the coil 34 is energized the core 61 is drawn in and the ratchet-wheel 80 is rotated counter-clockwise, thus turning the screw 86 to lower the table 16. By thus raising or lowering the table 16 the arc 18 is raised or lowered with respect to the predetermined or focus point.

The electro-responsive devices for controlling the operation of the raising and lowering mechanism are shown diagrammatically in Fig. 1, but they may be constructed as shown in Figs. 4 and 5. As here shown, the coils 23 and 30 are solenoids having slideable iron cores or plungers 100, 101, passing through guides 102, 103, and connected at their outer ends to springs 104, 105. The inner ends of the cores 100, 101, are connected to non-magnetic rods 108, 109, passing through guides 110, 111, and provided at their outer ends with casings 112, 114. Each casing houses a spring 115 which engages the opposing end of one of the rods 108, 109, and said springs also engage the inner ends of rods 116, 117, slideable in said casings. The rods 116, 117 are provided with contact blocks 118, 120, suitably insulated therefrom and adapted to bridge the stationary contacts 45, 46 and 37, 49, respectively. In this construction the contact blocks 118 and 120 are yieldingly supported and are adapted to adjust themselves to make a firm engagement with the stationary contacts when the coils are energized.

When the coils 23 and 30 are energized their cores 100 and 101 are drawn in and

the springs 104 and 105 are put under tension. In order to prevent a too rapid movement of the cores and connected parts when returning to normal position, a retarding-device or escapement is provided for each core. It comprises a shaft 125 journaled in bearings 126 and provided with blades or vanes 128. A ratchet-wheel 130 is affixed to the shaft 125 and is adapted to be engaged by a pawl 132 carried by the core of the solenoid. When the core is drawn back by its spring 104, or 105, the teeth of the pawl engage the corresponding ratchet-wheel to rotate the shaft 125, and the comparatively large surfaces of the vanes 128 produce a retarding action on said shaft.

The contact-member 20 is mounted upon a holder 140 which is yieldingly and slidably connected to a rod 141 passing through a guide 142. The inner end of the rod 141 is connected to the inner end of a magnetic-core 144 which is slideable within a solenoid coil 146, and is connected at its outer end to a spring 148.

The coil 146 is periodically energized to bring the contact-member 20 into engagement with one or the other of the electrodes 12, 14. To accomplish this a continuously running motor is provided, which may be of any well-known or suitable construction, although an electric-motor 150 is here shown, having its armature connected to wires 151 and 152, leading to the supply-wires. The motor is provided with a shaft 154 having a worm 155, which engages a worm-wheel 156 on a shaft 157, and the latter is provided with a worm 158, which engages a worm-wheel 159 on a shaft 160. Affixed to the shaft 160 is a drum 162, made of insulating material, preferably wood. Mounted on the periphery of the drum 162 is a contact-plate 164 having an overhanging upper edge and this plate is covered over a considerable portion of its area by an insulating plate 166, also having its upper edge overhanging. A pair of spring contact-arms 168, 169 are adapted to engage the periphery of the drum 162 and to slide up over the plates 166 and 164. As the arms 168, 169 move past the upper edge of the insulating plate 166 they are snapped quickly against the contact-plate 164, see Figs. 8 and 9, to make a good contact therewith and establish the circuit, and then as they move past the upper edge of the plate 164 they are snapped quickly against the periphery of the drum to break the circuit. The arm 168 is connected by a wire 170 to one end of the coil 146, the other end of said coil being connected by a wire 172 to the return-wire 48, of the supply circuit, and the arm 169 is connected by a wire 174 to the supply-wire 40. The driving-mechanism for the drum 162 is preferably so timed that the circuit

through the coil 146 is momentarily closed every three minutes or thereabouts.

The operation of this form of the invention is as follows:—

Normally the current passes from the electrode 12 across the arc 18 to the electrode 14, said electrodes being connected in circuit in a well-known manner. The current divides in the electrode 12, some passing through the wire 22, coil 23, wires 24, 31, coil 30 and wire 28 to the electrode 14. It will be noted that the coils 23 and 30 are in series, and they are so constructed that comparatively little current passes through them, not enough to attract their armatures.

When the plate 164 closes the circuit through the coil 146, said coil is energized and moves the contact-member 20 into engaging position. If the center of the arc 18 is in its correct position the contact 20 will engage both electrodes and there will be no effect on the coils 23 and 30 to move their armatures. Suppose, however, that the arc is below the required point, then the contact-member 20 will engage the upper electrode 12 and thus short-circuit the coil 23. This enables a larger portion of the current to pass through the coil 30 to energize it sufficiently to attract its armature 35 and bridge the contact-members 37 and 49. This closes the circuit through the coil 32, which thus becomes energized and drawn in its core 60. The pawl 74 engages the ratchet-wheel 76 and imparts a partial rotation to said ratchet-wheel and to the screw 86 to raise the table 16 and with it the lamp. The circuit through the coil 146 is then broken when the arms 168 and 169 leave the plate 164, and the spring 148 retracts the contact-member 20. If the arc is too high when the contact-member 20 is moved into engaging position the latter engages the lower electrode 14 and the coil 30 is short circuited. This allows the coil 23 to be energized sufficiently to attract its armature 53 and bridge the contact-members 45 and 46, thereby closing the circuit through the coil 34 which operates the mechanism in the housing 35 so as to lower the lamp and arc.

Contact 20 is adapted to be periodically moved into contact with the arc or its electrodes at some predetermined rate, say about once in three minutes. If it touches one of the electrodes the lamp is adjusted away from the contact until equal current flows in both relays, and then the lamp control ceases to act. The arc can now be displaced from the predetermined fixed point at which contact 20 is located by an amount equal to the difference in unequal carbon consumption during the period between adjustments. This shifting of the arc is, in practice, so small as not to affect the practical operation of the apparatus.

In Fig. 10 I have shown a modified form of apparatus, in which the contact-member which engages the arc is kept in continuous contact therewith.

5 As here shown 200 represents a housing for the arc lamp having an upper electrode 202 and a lower electrode 204, said lamp being mounted on an adjustable table or support 16, as explained above, and said electrodes being connected in circuit in any well-known manner.

10 A fixed contact-member 206 is mounted in a holder 207 which projects laterally from a stationary support 208 suitably secured in place, and this contact-member is adapted to engage the arc 209, the engaging end of said contact-member being located at the center of resistance of the arc, when the mathematical center of the arc is in line 20 with the optical center of the lens.

15 The upper electrode 202 is connected by a wire 210 to one end of a coil 211 of an electromagnet, and the other end of said coil is connected by wires 212 and 214 to the contact-holder 207 which is connected to the contact-member 206. The lower electrode 204 is connected by a wire 216 to one end of a coil 217, and the other end of this coil is connected by a wire 218 with the wire 214. 20 Thus there are two circuits having a common conductor 214 connected to the contact-member 206, each circuit having an electromagnet adapted to control the mechanism for moving the electrodes of the lamp in substantially the same manner as explained in the foregoing.

25 The mechanism for raising and lowering the lamp comprises a pair of electromagnet coils 32 and 34 arranged in a suitable housing 35 and connected with mechanism which raises and lowers the table 16, as heretofore explained.

30 One end of the coil 32 is connected by a wire 220 with a stationary contact-member 221, and the other end of this coil is connected by wires 222 and 223 to a supply-wire 224. One end of the coil 34 is connected by a wire 226 with a stationary contact-member 228, and the other end of the coil is connected by a wire 229 to the wire 223. A pair of stationary contact-members 230 and 231 are connected by wires 232 and 235, respectively, to the supply-wire 234. A double-throw switch blade 236 is 35 mounted on an arm 238 fulcrumed at 239 and provided with an armature 240 for the electromagnets 211 and 217. The operation of this form of the invention is as follows:—

40 Normally the greater portion of the current passes from the electrode 202 across the arc 209 to the electrode 204, said electrodes being connected in circuit in a well-known manner, and a small portion of the current passes through the wire 210, coil 211, wires

212, 214, holder 207, contact-member 206 to 65 electrode 204, and also wire 218, coil 217, and wire 216 to electrode 204. The current in the coils 211 and 217 is balanced so that the arm 238 remains in a central position when the center of the arc coincides with 70 the contact-member 206.

75 Suppose, however, that the arc center is below the center of the contact-member 206, then the portion of the arc extending between the contact-member 206 and the upper electrode 202 is shorter than the portion of the arc extending between the contact-member 206 and the lower electrode 204. Consequently, the resistance of that portion of the arc between the electrode 202 and the contact-member 206 is less than that between the contact-member 206 and the electrode 204. A larger current will therefore flow from the electrode 202 through the contact-member 206, holder 207, wires 214, 80 218, coil 217 and wire 216 to electrode 204. The coil 217 thus becomes energized sufficiently to attract the armature 240 and move the switch-contact 236 to bridge the stationary contact-members 221 and 231, 90 thereby closing the circuit through the coil 32 which actuates the mechanism for lifting the lamp. If the arc center should be above the predetermined point, the current would energize the coil 211 sufficiently to attract the armature 240 and close the circuit through the coil 34 which actuates the lowering mechanism.

95 In Fig. 11 I have shown an auxiliary source of current such as a storage battery 100 340, which is connected by a wire 341 to the upper electrode 12, and by a wire 342 to a coil 344 of a relay-switch, said coil being connected by a wire 346 to a contact 348. The coil 344 is provided with an armature 105 350 on a switch-arm 352 which is adapted to bridge contact-members 354, 355 connected in a controlling-circuit as explained above. In this figure circuit connections are shown for one electrode only, for simplicity, but, 110 in practice, the controlling circuit connected between electrode 14 and contact 348 contains a regulating relay with its operating battery in all respects similar to the relay 344 and battery 340, as shown. The operation of this form of the invention is substantially as heretofore described. When the arc becomes displaced and contact 348 comes into contact with say electrode 12, current from battery 340 flows between electrode 12, contact 348 and connecting wires to regulating relay 344, which energizes apparatus previously described to restore the arc to its normal position. When the arc becomes displaced in the opposite direction, 115 contact 348 comes into engagement with electrode 14, current flows through the other regulating circuit with its battery corre- 120 125

sponding to battery 340 and regulating relay corresponding to relay 344, and which circuit is not shown in the drawing, to adjust the arc to its normal position. In this 5 form of the invention the arc current is not utilized to operate the regulating relays, but a separate source of current, viz., batteries 340, are utilized for this purpose.

In Fig. 12 I have shown another modified 10 form of the invention, which comprises a housing 400 for the arc lamp having an upper electrode 402 and a lower electrode 404, said lamp being mounted on an adjustable support 406, as explained above, and said 15 electrodes being connected in circuit in any well-known manner.

The electrodes 402, 404 are connected by a shunt, composed of two branches 407, 408 having balanced resistances 410, 411 connected therein. A fixed contact-member 412 is mounted in a suitable holder and is adapted to engage the electrodes when the arc has moved from its correct position, as explained above. The contact-member 412 is 20 connected by a wire 414 to the armature of a reversing-motor 416, said armature being 25 also connected by a wire 418 to the junction of the branches 407, 408 of the shunt.

The motor 416 is provided with a shaft 30 420 having a worm 421 which meshes with a worm-wheel 422 on a vertical shaft 424, said shaft being screw-threaded at its upper end to coöperate with a correspondingly threaded bracket 426 secured to the adjust- 35 able support 406.

The operation of this form of the invention is as follows:—

When the arc is in its correct position, a portion of the current flows through shunt, 40 but not sufficient to operate the motor 416. If the arc is raised above the predetermined point, the lower electrode 404 will engage the contact-member 412, and the resistance 411 will be short-circuited. Thereupon an 45 increased current will flow through the shunt-branch 407 having the resistance 410, wire 418, armature of motor 416, wire 414, and contact-member 412 to the electrode 404, and the motor 416 will be driven in the di- 50 rection to cause the screw 424 to lower the support 406, and with it the lamp 400. If the arc becomes lowered below the predetermined point or optical center, the upper electrode 402 will engage the contact-mem- 55 ber 412, and the resistance 410 will be short-circuited. Thereupon an increased current will flow through the shunt-branch 408 having the resistance 411. This current will flow from the electrode 402 through the 60 contact-member 412, wire 414, armature of motor 416, wire 418 and branch 408 to electrode 404, said current being in the opposite direction from that just set forth above, and consequently the motor is driven in the

opposite direction to raise the lamp. The 65 motor 416 may be employed as an actuating-means when controlled by the other forms of controlling-means, which are shown in the other figures as well as when controlled by the means shown in Fig. 12.

It will be understood that the electrodes in all the various forms of the invention may, if desired, be inclosed from the atmosphere, thus increasing their life.

I claim:

1. The combination with the electric arc lamp having electrodes, of means for varying the position of said arc lamp, and means adapted to be brought into contact with the electrodes thereof at a predetermined 80 arc forming place for controlling the movement of said arc lamp, substantially as described.

2. The combination with an electric arc lamp having a pair of electrodes, of means 85 of adjusting said electrodes, and means adapted to be brought into electrical contact with the electrodes at a predetermined arc forming place to determine said arc forming place, substantially as described. 90

3. The combination with an electric arc lamp, of means for varying the position of the lamp to correspondingly vary the position of the arc, with respect to a predetermined fixed point, and means adapted to 95 be brought into contact with the arc for controlling the direction of movement of said lamp, substantially as described.

4. An electric arc lamp including a table, a screw for raising and lowering the table, 100 a pair of electrodes mounted on the table, a pair of electromagnets, means operated by said magnets for turning said screw in opposite directions to adjust the elevation of the table, to correspondingly adjust the 105 position of the arc between the electrodes with respect to a fixed point, and means affected by a change in the position of the arc to control the direction of movement of said table.

5. The combination with an electric arc lamp, of means for varying the position of the lamp, a pair of normally inoperative electro-responsive devices, controlling actuation of said means, and means for short-circuiting one of said devices when the center of the arc has moved away from a predetermined point, substantially as described. 115

6. The combination with an electric arc lamp, of means for varying the position of the lamp, a pair of normally inoperative electro-responsive devices controlling actuation of said means, and arranged to be operated by a portion of the current passing through the lamp, and means for short-circuiting one of said devices when the center of the arc has moved beyond a predetermined point, whereby the other of said de- 120 125

vices is actuated to operate the arc-varying means, substantially as described.

7. The combination with an electric arc lamp, comprising a pair of electrodes, of 5 electro-responsive means for raising and lowering the lamp, a contact-member arranged to engage said electrodes, and means connected to said contact-member arranged to control the operation of said raising and 10 lowering means, substantially as described.

8. The combination with an electric arc lamp, comprising a pair of electrodes, of 15 electro-responsive means for raising and lowering the lamp, a contact-member, means for periodically moving said contact member into and out of the arc space, and means connected to said contact-member for controlling the operation of said raising and lowering means, substantially 20 as described.

9. The combination with an electric arc lamp, comprising a pair of electrodes, of 25 a contact-member adapted to be brought into engagement with said electrodes, means for intermittently moving said contact-member into engaging position, and means for raising and lowering said lamp according as the center of the arc is below or above a predetermined point, substantially as 30 described.

10. The combination with an electric arc lamp, comprising a pair of electrodes, of

means for centering the arc, a contact-member adapted to electrically engage the arc at a predetermined point, a pair of opposed 35 electro-responsive devices arranged to control the operation of said centering means, said means being inactive when the center of the arc is at said predetermined point but adapted to be actuated by an unbalancing of the current flowing through said devices due to the movement of the center of the arc away from said predetermined point, substantially as described.

11. A self-focusing electric arc lamp, 40 comprising means for varying the height of the arc, a motor, a contact-device actuated by said motor, a circuit arranged to be momentarily closed by said contact-device, means controlled by said circuit for 45 engaging the electrodes of said lamp, and means controlled by the current of the arc circuit for actuating the means for varying the height thereof when its center has been moved away from a predetermined point by 50 an unequal consumption of the electrodes, substantially as described.

In testimony whereof, I have signed my name to this specification, in the presence of two subscribing witnesses.

JOHN L. BOYLE.
